H. GEISENHÖNER,
ELECTRIC HEATING APPARATUS,
APPLICATION FILED JUNE 21, 1920.

1,394,891.

Patented Oct. 25, 1921.

Inventor:
Henry Geisenhöner,
by *Albert G. Davis*
His Attorney.

UNITED STATES PATENT OFFICE.

HENRY GEISENHÖNER, OF SCHENECTADY, NEW YORK, ASSIGNOR TO GENERAL ELECTRIC COMPANY, A CORPORATION OF NEW YORK.

ELECTRIC HEATING APPARATUS.

1,394,891.

Specification of Letters Patent. Patented Oct. 25, 1921.

Application filed June 21, 1920. Serial No. 390,506.

To all whom it may concern:

Be it known that I, HENRY GEISENHÖNER, a citizen of the United States, residing at Schenectady, in the county of Schenectady, 5 State of New York, have invented certain new and useful Improvements in Electric Heating Apparatus, of which the following is a specification.

My invention relates to electric heating 10 apparatus and particularly to devices arranged to heat a plurality of articles by passing current therethrough in series.

The object of my invention is to provide a device which shall be simple and rugged 15 in construction, and which shall enable a high rate of output to be maintained without danger of burning the articles to be heated.

In my prior Patent No. 1,323,751, dated 20 December 2, 1919, I have described and claimed a method and apparatus for heating rivets and the like in series in a manner that insures a uniform product to be secured without skill on the part of the operator. 25 According to the present invention the capacity of the machine is increased while maintaining the advantages of series heating.

My invention will be better understood 30 from the following description taken in connection with the accompanying drawings and its scope will be pointed out in the appended claims.

Referring to the accompanying drawings 35 Figure 1 is a perspective view of my heating device with circuit connections to a source of current diagrammatically indicated; Fig. 2 is a detail view showing the electrode construction and this figure shows 40 a rivet to be heated inserted between the stationary and movable electrodes; Fig. 3 represents a modified form of electrode construction; Fig. 4 represents the use of the apparatus as a soldering iron heater, and 45 Fig. 5 represents the preferred electrode construction where the device is to be used for heating soldering irons and the like.

Referring to Fig. 1, electrodes 1, 2, 3 and 4 are mounted respectively on pivoted arms 50 5, 6, 7 and 8. Any convenient arrangement may be provided for independently moving the electrodes 1, 2, 3 and 4. This means is represented as a foot lever 9 connected to each electrode through an operating rod 10 55 having an insulating joint 11 therein. The

movable electrodes 1 and 2 are represented as coöperating with a stationary electrode or conducting member 12, and the movable electrodes 3 and 4 are represented as coöperating with a stationary electrode or 60 conducting member 13. The electrodes 12 and 13 are mounted upon a plate 14, each electrode being insulated from the plate 14 by an insulating member 15. The plate 14 is secured to the frame of the apparatus 65 which is represented as an angle iron structure comprising front legs 16 and 17, rear legs 18 and 19, and suitable bracing members. The bars 5, 6, 7 and 8 are mounted on the cross piece 20, suitable insulation 21 70 being provided to insulate each bar from the frame work. The plate 14 is adjustably secured upon the frame work by means of a wing nut 22 and a bolt arranged in a slot 23 provided in each end of the member 75 14. Holes 24 are provided in the plate 14 to permit a ready circulation of air to assist in keeping the electrodes cool. Each of the electrodes is indicated as provided with a corrugated surface to assist in keeping the same cool. An article to be heated, represented as a rivet 25, is shown interposed 80 between movable electrode 2 and stationary electrode 12, and rivets 25 are also represented as interposed between movable electrodes 3 and 4 and the stationary electrode 13. The movable electrodes are provided with curved contact faces to enable articles 85 of various lengths to be interposed between them and the stationary electrodes. 90

Current is supplied to the electrodes by means indicated as a transformer whose secondary winding 26 is connected to the bars 5 and 8. The current flows in series through the electrode and interposed articles to be heated, the circuit being traced from one terminal of the secondary winding 26 to the electrode 1; through the conducting member 12 to the electrode 2; through the flexible connection 27 to the 100 electrode 3, and through the conducting member 13 to the electrode 4, which is connected to the other terminal of winding 26. The heating current may be adjusted by varying the number of turns of the primary 105 winding 28 of the transformer.

In order to maintain the circuit completed whenever one of the articles 25 to be heated is removed, the apparatus is constructed and arranged so that the lowering of the movable 110

electrode will complete the circuit. According to the preferred embodiment of my invention this is accomplished by providing projections 29 on each of the conducting members, or electrodes 12 and 13, to engage the corresponding movable electrode when it is lowered. In Fig. 1 no rivet is indicated between the electrodes 1 and 12, and electrode 1 is consequently shown in the lowered position with the circuit completed between the electrodes 1 and 12 through the projection 29 which may be integral with electrode 12. In Fig. 2 a rivet 25 is shown interposed between electrodes 1 and 12, the circuit through projection 29 being broken at this time. This construction enables the apparatus to be used to heat one or any number of rivets less than the total number of pairs of coöperating contact surfaces on the electrodes. The auxiliary contact 29 in practical operation very quickly becomes covered with scale so that a substantial contact resistance is furnished at this point which prevents burning of any rivets which may be left in circuit.

Fig. 3 shows a modified arrangement in which the projection 29' is bolted to the electrode 12 instead of being made integral therewith, as shown in Fig. 2. I may in some instances make the projection 29 of iron or other material of substantially higher resistance than the copper electrodes 1 and 12, although this refinement in construction will generally be unnecessary.

Fig. 4 represents the use of my heating apparatus as a soldering iron heater. The soldering iron 30 is interposed between the copper electrodes 1 and 12 just as the rivet 25 is interposed in Fig. 2. The contact resistance between the copper soldering iron and the copper electrodes is so low that considerable sparking will take place when the circuit is interrupted, although the sparking is harmless. I have found that this arrangement will satisfactorily heat a soldering iron in about one-fifth of the time necessary with a gas furnace.

In order to reduce the sparking I prefer to construct the electrodes as shown in Fig. 5 when the device is to be used principally as a soldering iron heater. In this figure the soldering iron 30 is interposed between carbon blocks 31 and 32 which are clamped in the electrodes 1' and 12' by means of screws 33 and 34. In order to heat a soldering iron with the arrangement shown in Fig. 5 in the same length of time that is required with the arrangement shown in Fig. 4 the voltage of the primary circuit must be raised to about twice the value necessary with the arrangement shown in Fig. 4.

While I have shown and described certain specific embodiments of my invention

it will be obvious to those skilled in the art that many modifications and variations are possible, and I therefore aim in the appended claims to cover all such variations and modifications as fall within the spirit of my invention.

What I claim as new and desire to secure by Letters Patent of the United States is:—

1. An electric heating apparatus of the class described comprising a plurality of independently movable conducting bars, electrodes mounted on said bars and conducting means between which and the movable electrodes the articles to be heated are adapted to be interposed, said conducting means being arranged to complete a series circuit through said electrodes and articles to be heated, and means whereby said electrodes and conducting means coöperate to complete the circuit whenever an interposed article is removed.

2. An electric heating apparatus of the class described comprising a plurality of electrodes provided with a plurality of pairs of contact surfaces, said electrodes being arranged to be connected in circuit with a source of current, and arranged to complete a series circuit from such source through said electrodes and articles to be heated interposed between said contact surfaces, and means arranged to complete the circuit through said electrodes when an interposed article is removed from between a pair of said contact surfaces.

3. An electric heating device of the class described comprising a plurality of electrodes between which the articles to be heated are adapted to be interposed, means for supplying a current in series through said electrodes and interposed articles and means arranged to complete the circuit whenever an interposed article is removed.

4. An electric heating apparatus of the class described comprising a plurality of independently movable electrodes, and a conducting member between which and the movable electrodes the articles to be heated are adapted to be interposed whereby a current may flow in series through said electrodes and the articles to be heated, characterized by the fact that the electrodes are constructed and arranged so that the circuit is completed from an electrode and to the conducting member whenever an interposed article is removed.

5. In an electric heating device wherein means are provided for heating a plurality of articles in series, a pair of relatively movable electrodes provided with contact surfaces adapted to receive and hold an article to be heated, characterized by the fact that one of said electrodes is provided with a conducting projection arranged to engage the

- other electrodes of said pair when said electrodes are not held apart by an interposed article to be heated.
6. An electric heating device of the class described comprising a plurality of pivoted arms, means whereby said arms may be independently raised and lowered, an electrode mounted on each of said arms, conducting means arranged in coöperative relationship 10 to said movable electrodes, said electrodes and conducting means being provided with contact surfaces between which articles to be heated are adapted to be interposed and means on said conducting means adjacent 15 each movable electrode arranged to engage the same and complete a circuit of appreciable resistance between said electrodes and conducting means when said electrode is moved to its lowest position.
7. An electric heating device of the class described comprising a plurality of movable arms, means whereby said arms may be independently moved, an electrode mounted on each of said arms, conducting means arranged in coöperative relationship to said 25 movable electrodes, said electrodes and conducting means being provided with contact surfaces between which articles to be heated are adapted to be interposed, circuit connections whereby current may be passed in series through said electrodes, conducting means and interposed articles to be heated, and contact members on said conducting 30
- means arranged adjacent a plurality of said electrodes to engage the same to maintain the circuit completed when the articles to be heated are removed from between the corresponding contact surfaces.
8. An electric heating device of the class described comprising a plurality of pairs of pivoted arms arranged side by side, means whereby said arms may be independently operated to raise and lower the same, an electrode mounted on each of said arms, a stationary electrode arranged below and in 40 coöperative relationship to each pair of said movable electrodes whereby an article to be heated may be interposed between each of said movable electrodes and the coöperating stationary electrode, means whereby the outside electrodes may be connected to a source of current and means for electrically connecting the adjacent electrodes of adjacent pairs, whereby current may be passed in series through said movable electrodes, stationary electrodes, electrical connecting means and interposed articles to be heated, and contact devices arranged on said stationary electrodes to engage said movable electrodes when in lowered position to maintain the circuit completed whenever any of said interposed articles are removed.

In witness whereof I hereunto set my hand this 18th day of June, 1920.

HENRY GEISENHÖNER.
